UNITED STATES PATENT OFFICE.

ERNEST ALBERT INGOLD, OF LONDON, ENGLAND, ASSIGNOR TO W. & C. PANTIN, OF LONDON, ENGLAND.

CLUTCH MECHANISM PARTICULARLY APPLICABLE TO WIRE TWISTING OR TYING MACHINES.

Application filed April 26, 1924, Serial No. 709,235, and in Great Britain May 26, 1923.

The primary object of this invention is to provide a clutch mechanism connecting the driving and driven members of machines for binding or tying wooden or other boxes, bales or the like with hoops of wire, the ends of which are twisted together by causing them to overlap and gripping the overlap with one or more twisting pinions by means of which the two wires are twisted together on either side of the grip or grips.

In such machines it is found that when the twisting operation is completed the twisted part of the wire binds in the slot of the twisting pinion or pinions and prevents the ready ejection of the twisted wire therefrom, and that it is necessary for this purpose to relieve the strain upon the twisted wire and twisting pinion or pinions by rotating the latter through a suitable angle in the direction opposite to that by which the twisting of the wire is effected, the whole operation, including this reverse rotation, being effected by means of clutch mechanism which comes automatically into action at appropriate phases after a starting handle has been manually actuated.

It is to this clutch mechanism that the present invention relates and, although primarily designed with relation to wire twisting machines, it will be obvious that it is applicable to any machinery in which it is necessary after rotating a driving shaft in a given direction to a definite extent (which may be many or few turns or part of a turn) it is necessary for the shaft to be rotated automatically in the reverse direction to a definite extent.

The invention will be described more particularly with reference to its application to wire binding or twisting machines, whether these have one or more twisting pinions, any reference to the twisting pinion being understood to extend also to the case of machines with more than one such pinion, e. g. to machines having two oppositely rotated twisting pinions.

The invention is illustrated in the accompanying drawings as applied to a wire binding or twisting machine having two oppositely rotating pinions, Fig. 1 being a vertical section showing the essential parts of such a machine taken on line 1—1 of Fig. 2, which is a plan view showing the clutch and gearing of the machine but omitting the

twisting pinions and accessories carried by the top plate; Fig. 3 is a part vertical section corresponding with Fig. 1 but showing parts of the apparatus in a different working position; Figs. 4, 5, 6, 7 and 8 are detached views of various parts of the apparatus, Fig. 4 being a section on the line 4—4 of Fig. 1; Fig. 5 a section on the line 5—5 of Fig. 2; and Figs. 6 and 7 being sections on the lines 6—6 and 7—7, respectively, of Fig. 5.

In this machine there are provided two power wheels 1, 2 which rotate continuously in one direction one of them, which may be called the primary power wheel 1, being connectable by means of a clutch (hereinafter called the primary clutch) with a power shaft 4 by which the rotation of the twisting pinions 5, 6 is effected through suitable gear during the operation of twisting the wires, while the other or secondary power wheel 2 is brought into operation by means of a clutch 7 at a predetermined point in the twisting operation to actuate a cam shaft 8 by means of which various operations are performed or controlled, including the reverse rotation of the twisting pinions 5, 6.

The primary power wheel 1 is clutched with the power shaft 4 by means of a clutch pin 9 which is slidable axially in or upon a collar or disc 3 fast on the power shaft 4 and is projected at the appropriate moment into engagement with a dog 10, of which there may be one or more, or equivalent coupling element on the adjacent face of the primary power wheel 1. In the idle position, i. e. when the power shaft 4 is stationary, the clutch pin 9 is held against axial movement by a locking device 11 which is withdrawn automatically by the action of a cam 12, of which there are as many as there are clutch dogs 10, on the primary power wheel 1 to permit the clutch pin 9 to be shifted into driving engagement with the cooperating member 10. The locking device 11 may conveniently be in the form of a lever 11 (Fig. 4) fulcrumed as at 11^a upon the fixed collar or disc 3 and projecting into a slit 13 in the periphery of this disc so as to engage a notch 14 in the clutch pin 9, until the locking lever 11 is withdrawn by the engagement of a bowl or roller 15 carried upon an arm 16 projecting from the

tail of the lever with the cam 12 on the power wheel 1.

When the clutch pin 9 is locked by locking lever 11, its rear end extends into a guide aperture 17 extending through a disc 18 which is loose on the primary power shaft 4 and is capable of rotation through an angle determined by the position of two stops 19, 20, on the framing. In one of the limiting 10 positions, namely the starting position (Fig. 5), in which the fixed and free discs 3 and 18 are coupled by the clutch pin 9 and the latter is locked against axial displacement by lever 11, the clutch pin 9 is in alignment 15 with a slidably mounted spring-urged rod 21 which is normally held by a latch 22 and preferably adjustable stop 23 against the action of a spring 24, the release of which latch by means of the operating handle 25 20 acting through shaft 26 and lever 27 permits the sliding rod 21 to be forced by its spring 24 against the rear end of the clutch pin 9, so that, upon the withdrawal of the locking lever 11 the rod 21 shifts the clutch 25 pin 9 clear of the free disc 18 and into driving engagement with the clutch dog 10 on the primary power wheel 1. The rod 21 is then retracted and its spring 24 compressed by the action of a cam 28 on the 30 power shaft 4 engaging a collar 29 pinned on the rod 21, and the latch 22 is simultaneously restored to its initial position as in Fig. 3. The rod 21 is held in the position shown in Fig. 1 to prevent disengagement of 35 the clutch pin 9 by means of a spring-urged latch 30 which, when the power shaft 4 revolves, is returned by means of a cam 31 upon the end of the shaft to bring an aperture 32 of said latch into alignment with 40 the end of rod 21 which thereupon is retracted from the position shown in Fig. 1 to that shown in Fig. 3 by the action of the cam 28 against the collar 29 in opposition to the spring 24.

45 The end of the driven shaft 33 (Fig. 2), which is geared through pinions 4' and 33' with the primary power shaft 4, has a small crank pin 34 (Figs. 2, 5 and 6) projecting slightly beyond the end face of the shaft 50 which is flush with the framing (Fig. 6), and the free disc 18 has upon its face adjacent to the end of shaft 33 a recess 35 providing a ledge with which the crank pin 34 engages so as to shift a projecting arm 36 55 (Fig. 5) fast on the loose disc 18 from the upper stop 19 on the framing to the lower stop 20, whereupon the crank pin disengages the cooperating ledge. The arm 36 is restored to its upper position against stop 19 60 by the secondary or cam shaft 8 as herein-after described. The free disc 18 is held up against the top stop 19 in position for coupling with the fixed disc 3 by the end of the rod 21 which is urged to project to a slight 65 extent into the square guide aperture 17 in

the free disc 18. The rod 21 is retracted from this square aperture by the cam 28 to enable the crank pin 34 to turn the free disc 18 as above described.

When the continued movement of the power shaft 4 again brings the clutch pin 9 into alignment with the guide slot 17 in the free disc 18 the clutch pin 9 is forced rearwardly by the action of the surfaces of the clutch dog 10 and pin 9 out of driving engagement and into the position in which the free and fixed discs are again coupled. In the meantime the cam shaft 8 has become coupled with the secondary power wheel 2 through the secondary clutch 7 and continues to be driven thereby after the power shaft 4 has become declutched from the primary power wheel 1, in the manner described in U. S. Patent No. 1,486,396 of March 11, 1924, by means which form no part of the present invention.

A cam 37 on the cam shaft 8 engages a lever 37^a which is connected by a link 37^b with a lever 39. The lever 39 has one end fulcrumed on a pin carried by the framing and its other end engages with the arm 36 projecting from the free disc 18, so that, as the cam shaft 8 rotates, the disc 18 is rotated in the reverse direction until it reaches the first limiting stop 19, which determines the initial position. The consequent reverse rotation of the power shaft 4 through this definite angle effects the reverse movement of the twisting pinions 5, 6 necessary for the release of the strain on these pinions and on the twisting wire.

As shown in Figs. 1, 5 and 7 the two faces of the free disc 18 have circumferential recesses 40, 41 extending backwards from the guide slot 17, the recess 40 on the front side being provided to obviate any hammering action of the end of the pin against the face of the disc 18 and any possible deformation of the shoulder against which the crank pin 34 engages to rotate the free disc 18, while the recess 41 on the rear face is a sloping recess designed to guide a roller 42 on the clutch pin 9 gradually beyond the surface of the free disc 18, so as to ensure that the clutch pin will enter the guide slot 17 in the free disc 18.

The operation of the apparatus is as follows:—In the starting position the fixed disc 3 and the free disc 18 are coupled by the clutch pin 9, and the clutch pin 9 is locked against axial displacement by the lever 11 and is in alignment with the slidably mounted rod 21. The slidably mounted rod is held in the position shown in Fig. 3 by the latch 22 and adjustable stop 23 against the action of the spring 24. By turning the handle 25 the latch 22 is released from the stop 23 and the spring 24 is permitted to force the rod 21 against the rear end of the clutch pin 9, so that, when the lever 11 is

withdrawn from the notch 14 of the clutch pin 9 by the action of the cam 12 of the power wheel 1 upon the roller 15, the rod 21 shifts the clutch pin 9 clear of the free disc 18 and into driving engagement with the clutch dog 10 of the power wheel 1. The parts are then in the position shown in Fig. 1. During the first part of the rotation of the power shaft 4 the right hand end of the rod 21 remains in engagement with the loose disc 18 and the left hand end of the rod 21 abuts against the latch 30, which, upon the forward movement of the rod 21 has been forced upwardly by the action of its spring, and the disengagement of the clutch pin 9 from the clutch dog 10 is thereby prevented. After the power shaft has rotated through a predetermined angle, the latch 30 is depressed by the cam 31 on the end of the power shaft 4 so as to bring the aperture 32 of the latch into register with the end of the rod 21, whereupon the latter is thrust, by the action of the cam 28 upon the collar 29, to the left. The continued rotation of the power shaft 4 and the shaft 33 driven therefrom brings the crank pin 34 on the end of the driven shaft 33 into engagement with the ledge of the recess 35 in the free disc 18 and consequently turns the disc 18 counterclockwise (Fig. 5) through a definite angle which is determined by the disengagement of the pin 34 from the corner of the ledge in the recess 35, so that the arm 36 on the free disc 18 will be moved from its initial position against the stop 19 to the stop 20. When the continued movement of the power shaft 4 again brings the clutch pin 9 into alignment with the guide slot 17 in the free disc 18 the cam surface 10 of the clutch dog 40 on the power wheel 1, acting upon the cam surface at the right hand end of the clutch pin 9, pushes the clutch pin towards the left into the guide slot 17. The wheel 1 is then unclutched from the primary power shaft 4 and the clutch pin 9 lies entirely within the discs 3 and 18.

In the meantime the cam shaft 8 has become coupled with the secondary power wheel 2 through the secondary clutch 7 and continues to be driven thereby after the power shaft has become declutched from the power wheel in the manner described in the aforesaid United States Patent No. 1,486,396. The rotation of the cam shaft 8 effects the reverse rotation of the free disc 18 by engagement of the cam 37 on the shaft 8 with the lever 37^a which is connected through the link 37^b with the lever 39 and the arm 36 on the disc 18. The result of this reverse movement is to shift the arm 36 from against the stop 20, into which position it was moved by the pin 34 on the driven shaft 33, against the stop 19, which determines the initial position of the free disc 18. The reverse rotation of the free disc 18 effects the reverse

rotation of the power shaft 4, since the disc 18 is now clutched to the fixed disc 3, and this movement through a definite angle effects the reverse movement of the twisting pinions 5 and 6 and the clutch pin 9 is again brought into alignment with the sliding rod 21 and the apparatus is in position for the next operation.

The apparatus hereinbefore described may be modified in many respects without departing from the present invention, so long as the sequence of movements of the power shaft and the subsidiary shafts follow automatically upon the operation of the starting handle and the clutch pin is prevented by an automatically released lock from coming into engagement with the driving clutch except at the appropriate phase or position of the latter.

Having thus described the nature of the said invention and the best means I know of carrying the same into practical effect, I claim:

1. Clutch mechanism comprising a power shaft, a power wheel carried by said power shaft, an axially movable clutch pin, a clutch member on the power wheel co-operating with said clutch pin, means normally locking the clutch pin against axial movement, mechanism actuated by the rotation of the power wheel to release said locking means, a sliding rod axially aligned with the movable clutch pin, a latch normally engaging said rod to hold it in the operative position, and means carried by the power shaft and operative to withdraw said latch.

2. Clutch mechanism comprising a power shaft, a power wheel carried by said power shaft, an axially movable clutch pin, a clutch member on the power wheel cooperating with said clutch pin, a sliding rod axially aligned with the clutch pin and adapted to hold the clutch pin in the operative position, an automatically projected latch for engaging the rear end of said rod, and holding said rod in operative position, a spring tending to hold said rod in its operative position, a collar carried by said rod, a cam on the power shaft engaging said collar to retract said rod against the action of said spring, and a latch operating to hold said rod in its retracted position.

3. Clutch mechanism comprising a power shaft, a power wheel carried by said power shaft, an axially movable clutch pin, a clutch member on the power wheel cooperating with said clutch pin, a sliding rod axially aligned with the clutch pin and adapted to move and hold said pin in operative position, a latch automatically projected to engage the rear end of said rod, a spring normally urging said slideable rod into its forward or operative position, a collar secured on said rod, a cam associated with said power shaft and engaging said collar to re-

tract said rod against the action of said spring, an adjustable stop, a latch cooperating with said adjustable stop to hold said rod in its retracted position, and means including a starting lever to disengage said last-named latch from said stop.

4. Clutch mechanism comprising a power shaft, a power wheel carried by said power shaft, an axially movable clutch pin, a clutch member on the power wheel cooperating with said clutch pin, a sliding rod axially aligned with the clutch pin and engaging said pin to hold it normally in operative position, a latch actuated by the power shaft to engage the rear end of said rod, a spring normally urging said rod into its forward or operative position, a collar secured on said rod, a cam associated with the power shaft and engaging said collar to retract said rod against the action of said spring, an adjustable stop, a latch cooperating with said stop for holding said rod in its retracted position, and means including a starting lever for displacing said last-named latch to permit said spring to project the sliding rod forwardly and shift the clutch pin into its operative position.

5. Clutch mechanism comprising a power shaft, a power wheel carried by said power shaft, an axially movable clutch pin, a clutch

member on the power wheel cooperating with said clutch pin, an axially movable rod engageable with the clutch pin for holding said pin in operative position, an automatically projected latch for engaging the rear end of said rod, a spring normally urging said sliding rod into its forward or operating position, a cam associated with the power shaft for retracting said sliding rod against the action of said spring, an adjustable stop, a latch cooperating with said stop to hold said rod in its retracted position, means for displacing said last-named latch to permit the sliding rod to move the clutch pin into engagement with said power wheel, a disc normally loose on the power shaft and rotatable through a definite angle, means for limiting the angular movement of said loose disc, a shaft driven from the power shaft, a crank pin on said driven shaft operative to rotate the loose disc in one direction through said definite angle, means for coupling said loose disc to the power shaft, and cam-controlled means operative to revolve said loose disc through a definite angle in the reverse direction while coupled to the power shaft.

In testimony whereof I have signed my name to this specification.

ERNEST ALBERT INGOLD.
